(57) **CLAIM**

The ornamental design for a handle for an appliance, as shown and described.

DESCRIPTION

FIG. 1 is a front perspective view of the handle for an appliance showing my new design;

FIG. 2 is a front side elevation view thereof;

FIG. 3 is back side elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The dot-dash style broken lines in FIGS. 3 and 5 illustrate the boundary of the design, the region within this line being unclaimed.

The design is illustrated so that it is understood that the claim is not limited to a specific width.
